CLAIM

The ornamental design for a conduit dredge, as shown.

DESCRIPTION

FIG. 1 is a perspective view of a conduit dredge, showing my new design;

FIG. 2 is an another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
